DESIGN FOR AN INFANT'S BOOT

Berce L. Veach, St. Louis, Mo.

Application June 4, 1945, Serial No. 119,895

Term of patent 3½ years

(Cl. D7—7)

To all whom it may concern:

Be it known that I, Berce L. Veach, a citizen of the United States, residing in the city of St. Louis and State of Missouri, have invented a new, original, and ornamental Design for an Infant's Boot, of which the following is a specification, reference being had to the accompanying drawing, forming a part thereof.

In the drawing:

Fig. 1 is a top or plan view of an infant's boot, showing my new design;

Fig. 2 is a side elevation of the boot embodying my design, and

Fig. 3 is a side perspective view of the infant's boot shown in the other figures.

I claim:

The ornamental design for an infant's boot, substantially as shown.

BERCE L. V EACH.
